UNITED STATES PATENT OFFICE.

JOHN BEISWANGER, OF STEUBENVILLE, OHIO, ASSIGNOR TO GILL BROTHERS COMPANY, OF STEUBENVILLE, OHIO, A CORPORATION OF WEST VIRGINIA.

DESIGN FOR AN OVAL CASSEROLE.

57,183.

Specification for Design.

Patented Mar. 1, 1921.

Application filed October 31, 1919. Serial No. 334,861. Term of patent 14 years.

To all whom it may concern:

Be it known that I, JOHN BEISWANGER, a citizen of the United States of America, and resident of Steubenville, county of Jefferson, State of Ohio, have invented a certain new, original, and ornamental Design for an Oval Casserole, of which the following is a specification.

In the accompanying drawing I have illustrated an oval casserole, constructed in accordance with my invention, the same being of resistive transparent glass.

Figure 1 is a perspective view of an oval casserole showing my new design.

Fig. 2 is a bottom plan of the dish. Having thus described and illustrated my invention, I claim:

The ornamental design for an oval casserole, substantially as shown.

Signed by me at Steubenville, Jefferson county, Ohio, this 22nd day of October, 1919.

JOHN BEISWANGER.
